UNITED STATES PATENT OFFICE.

MARTIN B. McLAUTHLIN, OF MALDEN, AND JOHN W. DODD, OF QUINCY, MASSACHUSETTS, ASSIGNORS TO GEORGE T. McLAUTHLIN COMPANY, OF BOSTON, MASSACHUSETTS, A CORPORATION OF RHODE ISLAND.

ELEVATOR HOIST.

Application filed September 30, 1922, Serial No. 591,531. Renewed April 27, 1927.

This invention relates to elevator hoists having been more particularly designed for dumb waiter service and where electric drive is employed.

One object of this invention is to provide a construction by which the value of the starting current for the motor is reduced to a minimum and wherein a comparatively small motor is sufficient to move the elevator car with a rapid and easy positive and negative acceleration and a high maximum speed.

The reduction of starting current is a very important factor of economy which becomes particularly apparent where a number of hoists are actuated from the same circuit, since it materially reduces the maximum loads thereon and renders the load in a given period more nearly uniform. By reducing the starting current heavy overloads on the motor are eliminated and the motor overload protective devices may be set with a smaller margin so as to render them more effective in safeguarding the motor.

One factor which aids in the accomplishment of this object consists in causing the weight of the motor armature to act as a counterbalance for the elevator car.

Another factor resides in the construction of the winding drum.

A further feature of the invention resides in the winding mechanism whereby one of the limits of motion of the elevator car is precisely determined regardless of the exact position in which the motor comes to rest.

Other features and advantageous details and combinations of parts will appear from a more complete description of a preferred embodiment thereof disclosed in the accompanying drawings in which

Figure 1 is a top plan of the machine.

Figure 2 is a section on line 2-2 of Figure 1 with parts broken away.

Figures 3 and 4 are end and side elevations, respectively, of the winding drum and related parts.

Figure 5 is a top plan of the brake.

Figure 6 is a side elevation partly in section along the lines 6-6 of Figure 5 of the upper portion of the motor and the brake.

Figure 7 is an end elevation of the brake.

Referring to Figures 1 and 2, 1 indicates a casing transversely of which is journaled a winding shaft 2. This shaft extends outwardly at one side of the casing and carries the winding mechanism indicated generally at 3 and which will later be described more in detail. Within the casing the shaft 2 has fixed thereon a worm wheel 4. Extending inwardly from the lower portion of the casing opposite this worm wheel is a bearing lug 5 in which is journaled the lower end of a vertically extending shaft 6 which carries thereon a worm 7 meshing with the worm wheel 4. As shown the casing is formed in two parts, the lower part 8 extending upwardly and containing the lower halves of the bearings for the shaft 2 and the upper part 9 having therein the upper halves of these bearings and made fast to the lower section by means of bolts 10 passing through mating flanges 11 and 12 on the upper and lower sections, respectively. The casing thus furnishes a compartment in which the worm wheel and worm extend which may contain lubricant, and as shown an upwardly extending pipe 13 communicates with the interior of the section 8 and furnishes means by which lubricant may be supplied thereto.

Supported on the upper section 9 is a motor casing 15, the shaft 6 being the armature shaft for the motor, the armature being indicated at 16. This motor casing may be of any usual type such as is normally designed to operate with the armature in a horizontal position. With a motor of this type the feet 17 on which it is normally supported in the horizontal position furnish suitable supports to which a panel board 18 for the motor controlling devices may be attached. One end cap of the motor may be replaced by a cap 20 which may rest and be made fast on an outwardly directed flange 21 of the upper casing section 9. This cap is provided with a bearing opening 22 through which the shaft 6 passes and its lower face is preferably formed frusto conical in order to direct any lubricant which may be splashed thereon downwardly into the casing. To further prevent the escape of lubricant from this casing about the shaft, a deflecting shield, indicated at 23, may be

fixed to the shaft 6 immediately below the member 20. The armature shaft 6 extends upwardly and may be supported from the end cap 25 of the motor by ball bearings indicated at 26. Above the ball bearings 26 the shaft extends through a brake mechanism indicated generally at 30. With this construction the weight of the armature and shaft imparts a downward thrust on the worm wheel which serves to counterbalance to some extent the pull exerted by the winding cable on the drum 3.

This drum 3 is indicated in detail in Figures 3 and 4 and comprises a central circular portion 35 having a winding groove thereon for the cable, the portion 35 at opposite ends leading into portions of progressively smaller diameter toward the ends of the drum as indicated at 36 and 37, these portions having cable grooves therein forming continuations of the cable groove or path of the portion 35. The outer end of this drum terminates in a shoulder 38 which prevents the cable as wound on the drum from sliding endwise therefrom. The inner end of the drum has a one-direction clutch face 39 thereon. This face as shown comprises an inclined portion 40 terminating in a substantially axially arranged driving face 41. Cooperating with this clutch face is a mating clutch element 42. The drum is keyed to the shaft 2 while the clutch element 42 is slideable and rotatable thereon. The inner face of this clutch element has a shoulder 43 to prevent the slipping of the cable therefrom and the element is normally urged into clutching engagement with the drum by means of a coil spring 44 surrounding the shaft 24 reacting between it and a portion 45 of the casing 1.

The winding direction of the shaft 2 is such as to bring the driving face 41 of the clutch face against the clutch element 42 so as to impart a positive rotation thereto. In the unwinding direction, however, the driving is exerted through the inclined face 39 so that should resistance to the rotation of the clutch element 42 occur it may stop its rotation, being merely forced axially away from the drum against the pressure of the spring 44 by the action of the inclined face 39. The cable 46 to which the elevator car (not shown) is attached is wound on the drum and is made fast at the opposite end as by means of an eye bolt 47, to the clutch element 43. In this construction as the drum is turned to wind up the cable, the clutch element is positively driven as above described and the cable is wound starting on the clutch element, which has a small winding diameter, and from thence passing to the comparatively small diameter inner end portion of the winding drum. This small diameter causes the winding to be started at a comparatively slow rate and consequently

relieves the starting load on the motor to a very large extent. This is particularly desirable where alternating current motors are employed which are essentially constant speed motors and are not readily and economically controlled by speed-governing devices. The starting load on the motor is therefore reduced so that the rush of starting current is rendered small and the motor is not overloaded. As soon as the car is under way, however, the cable begins to wind on the increasing diameter of the drum so that its rate of speed is rapidly increased until it reaches the maximum where the cable is being wound on the large diameter central portion 35. It is then desirable to slow down the speed of the car in order that it may be brought to rest without shock, and for this purpose the final winding is effected on a gradually decreasing diameter portion of the drum until the cable is completely wound and the car has reached the desired limit of travel. At this point the current is cut off from the motor which is immediately stopped by the brake mechanism which will presently be described. When the drum is rotated in the reverse direction to pay out the cable the same action on the elevator car takes place. That is, it starts with a low velocity, is given a rapid positive acceleration, and then is given a rapid negative acceleration until it finally stops and this with a substantially constant motor speed. It is possible to so proportion the parts that the motor would be unable to start the car if the winding were started on the large diameter of the drum, but by starting on the small diameter it is amply able to accelerate the car to the speed produced by winding on the large diameter. A comparatively small motor, therefore, is thus fully capable of doing the work required. The clutch element 42, to which the end of the cable is attached, is used to insure a uniform limit of motion of the car on the unwinding of the cable. When the cable is all unwound, as shown in Figure 4, further rotation of the drum 3 in the unwinding direction, would tend to wind the cable in the reverse direction. As in this direction of rotation the clutch element is not positively driven, any tendency to rewind the cable effects a resistance to the rotation of the clutch element which in this direction is sufficient to stop its movement even though the drum 3 should rotate thereafter, the clutch element moving axially of the driving shaft 2 but not being rotated. This effects a constant limit of motion of the elevator car in one direction even though the winding drum should not stop its rotation precisely at the same point, as it may overrun without effecting the winding of the cable. When the drum is driven in the winding direction, however, a positive

clutching engagement is effected with the element 42 so that the cable starts to wind positively as the clutch element is not permitted to unclutch therefrom in this direction of rotation.

The braking mechanism above referred to is shown in detail in Figures 5 to 7. The armature shaft 6 as shown in Figure 6 extends above the motor casing cap 25 and has 10 fixed thereto a disk 50. As shown this disk is provided with a hub 51 through which passes a tapered pin 52 which also passes through a mating hole transversely of the shaft 6 and keys the two for simultaneous 15 rotation. Between the lower face of the disk 50 and the upper face of the cap 25 is positioned a ring shaped support 53 through the central opening of which the shaft 6 loosely passes and it is sufficiently thin so that it may have a slight vertical motion between the lower face of the disk 50 and the upper face of the cap 25. This support is prevented from rotating relative to the cap 25 by any suitable means. As shown this 20 means comprises pins 54 seated in perforations in the upper face of the cap 25 and extending into mating perforations 55 in the support 53. Above the plate 50 is positioned 25 a ring member 60 having at spaced points vertically perforated lugs 62. Through the 30 perforations in these lugs are passed rods 63 which are threaded at their lower end in portions 64 extending outwardly from the support 53 beyond the periphery of the disk 50. These rods 63 have thumb screws 65 35 threaded on their upper ends and bearing between the lower faces of these thumb screws and the upper face of the disk 60 are compression springs 66. These springs are so 40 positioned as to urge the ring 60 toward the support 53 so as to bring their opposed faces against opposite faces of the disk 50. These opposed faces are preferably provided 45 with frictional material of any suitable description as indicated at 70. When these 50 springs are allowed to act, therefore, the ring 60 is forced against the upper face of the disk 50 while the support 53 is raised upwardly from the top face of the cap 25 and 55 engages the lower face of the disk. This 60 normal position of the parts is then the position in which the armature shaft is braked against rotation. For the purpose of releasing this mechanism to permit free rotation of the shaft 6 electromagnetic devices 65 are indicated. Each device comprises an 65 electromagnet 72 carried by the support 53 and having passing through the central axis of its core 720 a non-magnetic push rod 73. 70 This rod engages the under face of the lug 62 between side flanges 74 depending therefrom on opposite sides of the core 720, and which prevent relative rotation of the ring 60 and the motor casing, since the support 75 65 is prevented from such relative rotation.

by means of the pins 55. The lower end of each core 73 rests loosely on an armature 75 loosely carried by screws 730 from the magnet frame 731 and which when the magnet is energized, is drawn upwardly against 70 the lower face of the magnet. The length of the rod 73 is so proportioned, however, that when the armature 75 is brought upwardly the lug 62 is pushed upwardly by the rod to force the ring 60 away from the support. This motion is sufficient in extent to permit the support 53 to drop down on to the upper face of the cap 25, thus entirely freeing it from engagement with the disk 50 and also to force the ring 60 upwardly to 80 an extent sufficient to disengage it from the upper face of this disk. When the magnet is deenergized the armature falls away therefrom and rests on the upper surface of a leaf spring 732 bridging the bolts 730, this spring 85 holding the armature, rod and lug in contact to prevent rattle. The magnets 72 are connected in the control circuit of the motor so that whenever the motor is energized these magnets are also energized, thus releasing the 90 brake. As soon as the motor-actuating current is broken these magnets fail to be energized and the springs 66 apply the brake as above described.

The machine as above described in which the motor is arranged vertically also provides a compact construction requiring little floor space and including the panel board of substantially constant horizontal dimensions throughout its height. It is thus capable of being employed in places where room is restricted. Furthermore the vertical position of the armature shaft facilitates ventilation of the motor, since air can pass to the armature through openings near the lower end of the motor casing and escape through the usual openings provided in the upper end cap.

It will be seen from the above description that a winding mechanism has been provided 110 which permits an easy and rapid motion of the elevator car with a comparatively small expenditure of energy, and while a preferred embodiment has been disclosed in the drawing, it should be evident to those skilled in 115 the art that many modifications and changes might be made therein without departing from its spirit or scope as defined by the appended claims.

We claim:

1. A machine of the class described comprising a winding drum, a cable to be wound on said drum, and a motor for actuating said drum having a rotating element, said rotating element being so disposed relative 125 to said drum that its weight acts thereon in opposition to the pull on the cable.

2. A machine of the class described comprising a winding drum, a cable to be wound on said drum, and a motor for driv- 130

ing said drum, said motor having a part acting by its weight on said drum in a direction opposed to the pull of the cable thereon.

3. A machine of the class described comprising a winding drum, a cable to be wound on said drum, a worm wheel fixed to rotate with said drum, a vertically positioned worm meshing with said worm wheel, and a motor rotor fixed to said worm to impart by its 10 weight an axial thrust on said worm acting in opposition to the pull of the cable on said drum.

4. A machine of the class described, comprising a winding drum, a cable to be wound 15 on said drum, a worm wheel fixed to rotate with said drum, a casing for said worm wheel, a motor supported by said casing, said motor having a vertically arranged armature, a worm fixed to rotate with said 20 armature and meshing with said worm wheel, the weight of said armature and worm acting on said drum in opposition to the pull exerted thereon by said cable.

5. A machine of the class described comprising a casing, a shaft journaled horizontally in said casing, a worm wheel fixed to 25 said shaft within said casing, a motor fixed to the top of said casing and having its

rotor arranged vertically, a rotor shaft extending downwardly into said casing, a 30 worm fixed to said shaft and meshing with said worm wheel, said casing being constructed to receive a lubricant in which said worm and worm wheel extend and a lubricant deflector carried by said shaft about 35 said worm acting to prevent the passage of lubricant out from said casing about said shaft.

6. In a device of the class described, a shaft, a winding drum fixed to said shaft, 40 said drum having a central winding portion of comparatively large diameter and end portions of progressively decreasing winding diameters in directions away from said central portion, an element having a small winding diameter slideable and rotatable on said shaft, said drum and element having 45 mating one-direction clutch faces, means normally urging said element into clutching relation to said drum, and a cable to be 50 wound on said element and drum having one end fixed to said element.

In testimony whereof we have affixed our signatures.

JOHN W. DODD.

MARTIN B. McLAUTHLIN.
